PROCESS FOR THE MANUFACTURE OF UN-
SATURATED FATTY ACIDS

Karl Hennig, Rosslau in Anhalt, Germany, assignor to Deutsche Hydrierwerke Aktiengesellschaft, Berlin-Charlottenburg, Germany, a corporation of Germany

No Drawing. Application December 13, 1935, Serial No. 54,298. In Germany December 15, 1934

7 Claims. (Cl. 260—413)

It is known to saponify spermaceti or spermaceti oil by alkalis at higher temperatures whereby the fatty alcohols contained in these fatty products as constituents of the esters are converted into fatty acids. Probably in the presence of unsaturated fat-stuffs reactions occur corresponding to the so-called Varrentrapp reaction, i. e., the unsaturated oleic acid is decomposed to saturated palmitic acid forming 10 the soap of this fatty acid on fusion with alkali.

Now it has been found that the action of the alkali on the mixtures of fatty alcohols occurring in the oils of sea animals or their esters, particularly the naturally occurring esters such as sperm oil or arctic sperm oil may be so conducted that the double links existing in the raw materials are preserved by maintaining certain limits of alkali, temperature and concentration, but particularly by applying superatmospheric pressure. In this manner unsaturated fatty acids are formed in a practically quantitative yield from unsaturated fatty alcohols and likewise from such esters which contain only unsaturated fatty acid and unsaturated fatty 25 alcohol components. The so-called Varrentrapp reaction, i. e., the formation of a saturated fatty acid from an unsaturated fatty acid under loss of two carbon atoms is entirely eliminated by avoiding excess of alkali and passing beyond certain limits of temperature. This observation is 30 novel and renders it possible to perform the manufacture of oleic acid and its homologues in a very simple way. It is only necessary to separate from the naturally occurring mixtures of unsaturated fatty alcohols or their esters, particularly naturally occurring esters like sperm oil or arctic sperm oil the portions which are solid in the cold by known processes from the raw materials. Often, for instance, a simple 35 freezing out process is sufficient. The residual fluid of highly unsaturated oil is then converted into a soap in the method detailed below. Decomposition of the soap with acid yields finally an oleic-acid-like mixture of fatty acids. The 40 product of reaction itself, or after distilling or fractionating, is an excellent mixture of unsaturated fatty acids which may be used in the refining processes of textiles, in the production of textile assistants and in all cases in which 45 heretofore oleic acid (so-called oleine) from tallow was applied.

The conversion of the naturally occurring mixtures of fatty alcohols or their esters, e. g., sperm oil to fatty acids of oleic-acid-like nature is performed by first separating the solid portions

of the raw materials by filtration in the cold or by other suitable processes and after addition of the necessary amount of alkali metal and alkaline earth metal hydroxides or mixtures thereof by gradually heating while stirring at temperatures over 200° C. advantageously between 200° to 280° C. The alkali or earth alkali hydroxides are used preferably in a small excess and are mixed with 10 to 30% of their own weight of water. The reaction ensues with formation of the salt of the fatty acid, hydrogen being set free. When using esters as starting material a saponification of the esters first takes place and then the alcohols formed are converted 10 to acids. The process is suitably performed under elevated pressure in such a manner that the hydrogen formed is allowed constantly to blow off, taking along the vapors of the water added previously to the reaction mixture. The end of 15 the reaction is recognized when the evolution of the hydrogen gas stops. The formed soap is decomposed with acids. By this method a mixture of unsaturated fatty acids of the type of oleic acid is obtained which not only resembles by colour, odour and physical and chemical constants the oleic acid obtained by the stearin process by pressing off the tallow but it is also like that product which is free of highly unsaturated easy inflammable and chemically unstable higher molecular weight unsaturated acids. 20 Therefore it is suitable not only for greasing purposes but also for the manufacture of textile soaps and textile soap preparations, for sulfonates 25 for emulsion purposes and so on.

The proposed method for the manufacture of 30 valuable oleine is a new one and provides for obtaining those products from cheap raw materials not fit for food or for the manufacture of soaps, without troublesome pressure extraction or protracted fractional distillation. Therefore 35 it is possible to make mixtures of high molecular unsaturated fatty acids in a more satisfactory way.

The process above may also be performed by immediately submitting without previous filtration the raw materials to the fusion with alkali and then after decomposition of the formed soap separating by filtration the solid saturated fatty acids from the fluid unsaturated fatty acids of 40 the type of oleic acid.

Example 1

500 parts by weight of technical oleyl alcohol, (iodine number 75) as obtained by cooling down to -15° C. and filtering in a cooled press the 45 50

mixture of fatty alcohols from the saponification of sperm oil, and 90 parts by weight of caustic soda and 25 parts by weight of water are slowly heated in an autoclave up to 250° C. while stirring. At this temperature the splitting off of the hydrogen sets in and produces pressure in the autoclave which by constant blowing off is maintained at 5 atmospheres. Hereby the water previously added is distilling off. The temperature is slowly raised to 276-280° C., the quantity of hydrogen split off being a measure for the progress of the reaction. As soon as the evolution of hydrogen is over the reaction mixture is cooled down and the formed soap is decomposed by diluted sulfuric acid. An oleic acid with the iodine number of 68-70 and a content of 96-97% saponifiable fat is obtained.

Example 2

500 parts by weight of sperm oil or arctic sperm oil (iodine number 85) are worked up in the same manner as in Example 1 with 100 parts by weight of caustic soda and 25 parts by weight of water. The solid portions of the sperm oil or arctic sperm oil are separated in the manner described in Example 1. 515 parts by weight of a mixture of unsaturated fatty acids are obtained (saponification number 202, iodine number 78-80, stock point 3°). The mixture is suitable generally as a substitute for the usual oleic acid.

30 I claim:

1. The process for the manufacture of unsaturated fatty acids which comprises separating from sperm oil the saturated portion which is solid at low temperatures, reacting the residual fluid portion with alkali of the group consisting of alkali metal and alkaline earth metal hydroxides in a slight excess at a temperature above 200° C. and under super-atmospheric pressure until the esters present are saponified and alkali salts of unsaturated fatty acids are formed from components of the esters and reacting the unsaturated fatty acid salts with a mineral acid to produce unsaturated fatty acids.

2. The process for the manufacture of unsaturated fatty acids which comprises separating from unsaturated fatty alcohol mixtures obtained from the oils of sea animals the saturated portion which is solid at low temperatures, reacting the residual unsaturated fluid portion with alkali of the group consisting of alkali metal and alkaline earth metal hydroxides in a slight excess at a temperature between about 200 and about 280° C. and under super-atmospheric pressure until the same is converted to alkali salts of unsaturated fatty acids and reacting the unsaturated fatty acid salt with a mineral acid to produce unsaturated fatty acids.

3. The process for the manufacture of unsaturated fatty acids which comprises separating

from mixtures of esters occurring in the oils of sea animals the unsaturated esters fluid at low temperatures, reacting the same with alkali of the group consisting of alkali metal and alkaline earth metal hydroxides in a slight excess at 5 a temperature above 200° C. and under super-atmospheric pressure until the esters present are saponified and alkali salts of unsaturated fatty acids are formed from both components of the esters and reacting the unsaturated fatty acid 10 salts with a mineral acid to produce unsaturated fatty acids.

4. The process for the manufacture of unsaturated fatty acids which comprises reacting a mixture of unsaturated fatty alcohols obtained 15 from the oils of sea animals with alkali of the group consisting of alkali metal and alkaline earth metal hydroxides in a slight excess at a temperature between 200 and 280° C. and under a pressure of about 5 atmospheres until the same is 20 converted to alkali salts of unsaturated fatty acids and reacting the unsaturated fatty acid salts with a mineral acid to produce unsaturated fatty acids.

5. The process for the manufacture of unsaturated fatty acids which comprises reacting a mixture of unsaturated fatty esters obtained from the oils of sea animals with alkali of the group 25 consisting of alkali metal and alkaline earth metal hydroxides in a slight excess at a temperature between about 200 and about 280 C. and under a pressure of about 5 atmospheres until the esters present are saponified and alkali salts of unsaturated fatty acids are formed from both 30 components of the esters and reacting the unsaturated fatty acid salts with a mineral acid to produce unsaturated fatty acids.

6. The process for the manufacture of unsaturated fatty acids which comprises reacting material of the group consisting of unsaturated 40 fatty alcohols and esters of unsaturated fatty alcohols with alkali of the group consisting of alkali metal and alkaline earth metal hydroxides in a slight excess at a temperature above 200° C. and under superatmospheric pressure until 45 the same is converted to alkali salts of unsaturated fatty acids.

7. The process for the manufacture of unsaturated fatty acids which comprises reacting material of the group consisting of unsaturated fatty 50 alcohols and esters of unsaturated fatty alcohols with alkali of the group consisting of alkali metal and alkaline earth metal hydroxides in a slight excess at a temperature between about 200 and about 280° C. and under a pressure of about 5 atmospheres until the same is converted to alkali 55 salts of unsaturated fatty acids.

KARL HENNIG.

CERTIFICATE OF CORRECTION.

Patent No. 2,159,700.

May 23, 1939.

KARL HENNIG.

It is hereby certified that error appears in the printed specification of the above numbered patent requiring correction as follows: Page 2, first column, line 10, for "276-280° C." read 270-280° C.; line 40, after "from" insert the word both; and that the said Letters Patent should be read with this correction therein that the same may conform to the record of the case in the Patent Office.

Signed and sealed this 4th day of July, A. D. 1939.

Henry Van Arsdale

Acting Commissioner of Patents.
